UNITED STATES PATENT OFFICE.

GEORGE H. STEADMAN, OF PASSAIC, NEW JERSEY.

DESIGN FOR A SPONGE-CUP.

SPECIFICATION forming part of **Design No. 25,755**, dated July 7, 1896.

Application filed October 18, 1895. Serial No. 566,165. Term of patent 3 years.

To all whom it may concern:

Be it known that I, GEORGE H. STEADMAN, a citizen of the United States, residing at Passaic, county of Passaic, and State of New Jersey, have invented a certain new and ornamental Design for Sponge-Cups, of which the following is a specification.

In the drawings which accompany and form a part of this specification, Figures 1 and 2 represent, respectively, a plan and a transverse section of my holder for wet sponges.

The leading feature of my design consists in an interiorly-projecting ledge or rim located at the top of the sponge-holder proper.

A is my cup, provided with an open top A'

and with a ledge or rim a, located near the open top or mouth of the cup, which cup is also provided with orifices a', and is seated in the holder or bowl B.

What I claim is—

The design for a sponge-cup substantially as herein shown and described.

In testimony of the foregoing specification I do hereby sign the same, in the city of New York, county and State of New York, this 10th day of May, A. D. 1895.

GEORGE H. STEADMAN.
